P. H. NEIDIG.

DOOR LATCH.

APPLICATION FILED FEB. 19, 1921.

Patented Feb. 7, 1922.

BY

Watson E. Coleman

ATTORNEY.

UNITED STATES PATENT OFFICE.

PERCY H. NEIDIG, OF MADISON, NEBRASKA.

DOOR LATCH.

1,405,857.

Specification of Letters Patent.

Patented Feb. 7, 1922.

Application filed February 19, 1921. Serial No. 446,323.

To all whom it may concern:

Be it known that I, PERCY H. NEIDIG, a citizen of the United States, residing at

Madison, in the county of Madison and State of Nebraska, have invented certain new and useful Improvements in Door Latches, of which the following is a specification, reference being had to the accompanying drawings.

10 This invention relates to door latches, and particularly to that variety of door latch wherein two oppositely shiftable bolts are provided upon the inside of the door and so connected to a handle that when the handle is rotated in one direction the bolts are simultaneously projected into engagement with suitable keepers, and when the handle is operated in the opposite direction both of the bolts are retracted.

20 The general object of this invention is to provide a latch of this character which is very simply constructed and which may be readily assembled and put together, in which the handle, when shifted to its door latching position, is adapted to be latched by means of a padlock or like engaging device.

25 A further object is to provide a lock of this character which is adapted to be opened from both the inside and the outside of the door except when the padlock is in place, and in which the operating lever is adapted to strike stops when the bolts are fully projected or fully retracted.

30 Other objects will appear in the course of the following description.

35 My invention is illustrated in the accompanying drawings, wherein:—

Figure 1 is a perspective view of a portion of a door and sill thereof showing my 40 latch in place and looking toward the inside of the door, the lintel of the door being partly in section;

Figure 2 is a perspective view looking toward the outside of the door and showing 45 the face plate and handle;

Figure 3 is a perspective view of the plate 27;

Figure 4 is a perspective view of the member 31;

50 Figure 5 is a perspective view of the handle and shank;

Figure 6 is a perspective view of the extremity of the shank;

Figure 7 is an elevation of one of the 55 latching bolts;

Figure 8 is a sectional view through the

squared end of the shank showing the manner in which the plate 31 is engaged with the shank.

Referring to these drawings, A designates 60 a door, B the door sill, and C the lintel of the door. Mounted upon the inside face of the door A is a metallic plate 10 which is vertically slotted at one side so that a tongue of metal 11 is formed which is to be turned 65 down into a position at right angles to the plane of the plate 10 and constitutes a stop. The center of the plate 10 is perforated for the passage of the shank 12 of an operating handle 13, the handle being disposed upon 70 the exterior face of the door. This shank 12 extends through the aperture in the plate 10 and the inner extremity of the shank is reduced in thickness, as at 14, the edge faces of this reduced portion being formed with 75 interrupted screw-threads, as at 15, for engagement by a nut 16. Carried upon this portion 14 of the shank, which is rectangular in cross section, is an operating lever 17 which is formed of a strip of metal outwardly bowed at its middle and formed with a rectangular aperture 18 through which the rectangular portion 14 passes and with two laterally directed portions formed with apertures 19, one of these portions having 80 an upwardly and outwardly projecting handle 20.

Bolts 21 are engaged with the apertures 19, the extremities of the bolts being laterally bent to pass through these apertures and held in place by cotter pins 22. One of the bolts extends upward and the other downward, and both of these bolts are designed to pass through guides formed by plates 23 having U-shaped members 24 attached to 90 them and projecting outwardly from the plates and through which the bolts pass. These plates are attached to the door by means of screws. Attached to the sill and to the lintel respectively are the keeper plates 25 which are longitudinally slotted, as at 26, and into which the bolts 21 are adapted to 95 be projected. The sill and lintel respectively are recessed below these apertures to receive the bolts.

The shank 12 of the handle 13 passes through a plate 27 attached to the outer face of the door by means of screws 27^a, this plate being approximately diamond-shaped in face view, the lower end of the plate having an outwardly projecting lug 28 having 100 an aperture 29. The shank 12 inward of the

handle 13 is formed with two oppositely disposed recesses 30 and engaged with this shank 12 is a metal strip 31 which is angularly bent, one arm of this strip being longitudinally slotted, as at 32, the other arm being perforated, as at 33. This strip constitutes an angular arm which rotates with the shank of the handle. The bifurcated end of this strip is adapted to be disposed within the recesses 30 and then the extremities of the fork or bifurcation are forced inward over the shank, as illustrated in Figure 8, so that this angular arm 31 is mounted upon the shank for oscillation therewith.

15 When the handle is in one position and the bolts 21 are projected into engagement with the lintel and sill respectively, the arm 31 is in such position that its opening 33 is in alignment with the opening 29. Under these 20 circumstances a padlock may be placed through these openings, thus locking the handle from any return movement which would act to retract the bolts. When the padlock is removed, it is obvious that the 25 handle may be shifted to retract the bolts. When the handle is shifted into a vertical position, that is into a position wherein the aperture in the arm 31 is brought into alignment with the aperture 29, then the lever 17 30 will be turned into an approximately vertical position and the edge of this lever will bear against the edge of the stop 11. When this lever 17 is turned to a horizontal position to fully retract the bolts, then the lever 35 will engage with the upper face of the stop 11. Thus this stop acts to limit the movement of the lever and of the handle in opposite directions. The handle 20 forms means whereby the lock may be operated from inside 40 the barn, garage or other building to which it is to be applied.

This device is particularly intended for use on double swinging doors such as are used on garages, barns, stables and the like but, 45 of course, it may be applied to other uses. It will be seen that the device is very simple, easily operated, and that it forms an inside lock both at the top and bottom of the door, the locking device itself being, however, at 50 the middle of the door. Ordinarily double doors are locked usually at the middle of the meeting edges of the door and thus the upper portion of the door may be pried outward or the lower portion thereof with the consequent likelihood of bursting the door, but by 55 providing bolts at the upper and lower ends of the door, the upper and lower ends of the door are held firmly against any attempt to pry them open and there must be a break of 60 the latch itself in order to permit the opening of the door.

The plate 27, as before stated, is held to the door by means of screws 27^a, and it will be seen from Figure 2 that one of these 65 screws 27^a is disposed in such position that

it is closed by the arm or plate 32 when the opening 33 is in alignment with the opening 29. Thus when a padlock is placed through these openings 33 and 29, the lower screw 27^a is entirely concealed and cannot be removed, though the upper screw, of course, may be removed. Thus it would be impossible to open the lock without breaking it. The lock holds the door securely and offers a very considerable protection against any one 75 who might want to open it without a key for the padlock. The arm 31 is to be made of relatively heavy sheet metal and when the slotted end of this arm is closed upon the neck 30 of the spindle 12, the arm 31 will be 80 firmly held against being detached from the spindle 12.

I claim:

1. A latching means for doors including a plate having an outstanding apertured lug, a handle having a shank extending through the plate and oscillatable therein, an arm extending from the shank and disposed parallel to the plate, said arm having an angularly bent extremity formed with an aperture adapted to align with the aperture in the plate whereby a padlock may be inserted through the two apertures to hold the handle shank from oscillation.

2. The combination with a door, of a handle having a shank extending through the door and oscillatable therein, a lever mounted upon the inner end of the handle shank and extending in opposite directions, oppositely extending bolts connected to opposite ends of the lever and projectible by rotating the handle shank in one direction and retractible by rotating it in the other direction, a fixed apertured member mounted upon the exterior of the door, and an apertured arm carried by the handle shank and rotatable into alignment with the apertured member whereby a padlock may be inserted through the two apertures to hold the handle shank from rotation to a position to 105 retract the bolts.

3. The combination with a door and a sill and lintel, of a handle having a shank rotatably mounted in the door, a lever mounted upon the inner end of the shank and extending in opposite directions therefrom, upwardly and outwardly extending bolts pivotally connected to the ends of the lever, guides on the inner face of the door through which the bolts pass, slotted keepers mounted upon the lintel and sill respectively and into which the bolts are adapted to be projected, a stop limiting the rotation of the handle shank, an apertured member mounted upon the door, and an arm carried 115 upon the handle shank and having an apertured extremity adapted to be brought into register with the aperture of the fixed member and through which apertures a padlock 120 may be passed.

4. A latch of the character described including a plate adapted to be attached to the inside of a door, a handle having a handle shank extending through the plate, the inner 5 end of the handle shank being rectangular and having interrupted screw-threads, a lever having a rectangular aperture through which the rectangular end of the shank passes, a bolt engaging the screw-threads of 10 said shank and holding it to the lever and the lever against said plate, upwardly and downwardly extending bolts pivoted to the extremities of the lever, said lever being formed at one end with a handle, a stop 15 formed upon the plate and limiting the movement of the lever, said handle shank adjacent the handle being formed with oppositely disposed recesses, an arm slotted at one end to fit over said recesses and be held in 20 rotative engagement with the handle shank, the end of the arm being angularly bent and apertured, and a plate inward of said arm through which the handle shank passes, the plate having an outwardly projecting apertured lug with which said arm is adapted 25 to align whereby a padlock may be placed through said apertures.
5. The combination with a door, of latching means therefor including an oscillatable handle having a shank extending through 30 the door, a lever carried upon the inner end of the shank, a vertically movable bolt operatively connected to the lever, a plate mounted upon the exterior face of the door and having an angularly bent, perforated end, 35 an arm mounted upon the handle shank and having an angularly bent, perforated end adapted to align with the angular end of the plate and permit the passage of a padlock therethrough, and a screw holding the plate 40 against the door and disposed through that portion of the plate covered by the arm when the door is locked.
6. A latch of the character described including a plate adapted to be attached to a door, a handle having a handle shank extending through the plate, door locking means operatively connected to the shank to be actuated by an oscillation of the shank, an apertured lug formed upon the plate and 45 outwardly projecting therefrom, and an arm carried upon the handle shank and disposed in parallel relation to the plate and having an apertured angular extremity adapted to align with the apertured lug of the plate 50 whereby a padlock may be placed through said apertures to lock the handle shank from movement.

In testimony whereof I hereunto affix my signature.

PERCY H. NEIDIG.
